ATTORNEY

UNITED STATES PATENT OFFICE

WALLACE H. BRACKEN, OF RYE, NEW YORK

LUGGAGE TRAY

Application filed January 7, 1931. Serial No. 507,174.

My invention relates to improvements in clothes holding trays for hand luggage such as suit cases and it is my object to give such hand luggage the advantages of wardrobe trunks so far as carrying suits of clothes is concerned, in a light, simple and inexpensive manner.

In the drawing Fig. 1 is a perspective view of my improved tray; Fig. 2 a top view of the tray with the flap partly broken away; Fig. 3 a detail, sectional view of the structure of Fig. 2 on the line 3-3 thereof; Fig. 4 a detail view of the structure of Fig. 3 on the line 4-4 thereof; and Fig. 5 a detail, fragmentary view of the coat hanger used in my tray.

The tray proper comprises a bottom 1, a back 2 and ends 3 and 4, but no front. A flap 5 is secured to the back by a flexible strip 6 which strip and flap have an opening 7 therein. The main portion of the flap 5 does not extend to the ends of the tray but the ends are stepped at 8 and 9 as shown in Fig. 1.

Directly under the opening 7 a post 10 is secured to the bottom of the tray. This post is squared and has a shoulder 11 intermediate its length and preferably terminates at its upper end in a pyramid as shown.

The coat hangers 12 and 13 are each provided with a metal clip 14 which is provided with a squared hole 15 to engage the post 10, the hole in the lower hanger being larger than the hole in the upper hanger so that it will slide down the post to the bottom of the tray while the upper hanger will slide down the post until it rests on the shoulder 11, the pyramidal top to the post facilitating easy engagement of post and hangers. As the squared holes fit the squared post the hangers cannot shake around in the tray.

The coat hangers may be provided with folding hooks 16 which may be swung clear of the holes in the hanger clips and lie over the hanger proper.

To pack the clothing the tray is removed from the suit case and the flap 1 thrown back and the hangers removed. A coat is then hung on the lower hanger and the hole in the clip is slipped over the post, the lower part 50 of the coat and sleeves extending beyond the

front of the tray. The vest is next folded and laid on the coat within the tray. The second coat is then placed on the upper hanger and the hole in its clip is slipped over the post with the lower part of the coat and sleeves extending beyond the front of the tray. The vest is then folded and laid on the second coat within the tray. A pair of trousers is then folded and placed in the tray with the seat portion therein and the legs extending beyond the end of the tray. The second pair of trousers is next folded and laid in the tray with the seat therein and the legs extending beyond the opposite end of the tray. The flap 5 is then turned down over the suits in the tray after which the lower portions of the coats and sleeves are turned up and folded over the free edge of the flap. The trousers are successively folded over the notched ends of the flap and lie on top of the folded lower portions of the coats, the space between the ends of the flap and the ends of the tray permitting the folded trousers to lie wholly within the tray.

The flexible section 6 joining the flap 5 and back 2 accommodates the flap portion to any thickness of clothing and allows the flap to hold the clothing stationary without shifting. If but one suit is to be carried the opening 7 enables the post 10 to pass through the opening in the flap and flexible strip and allows the flap to lie flatly against the portions of the garments below it.

The steps 8 and 9 in the flap prevent the trousers sliding down to the back of the tray and becoming wrinkled.

The tray is placed in the suit case with the free edge of the flap adjacent the carrying handle so that the clothing will hang over the edge of the flap and cannot slide around and wrinkle.

When the tray is unpacked the hook 16 is swung up, the vest and coat placed on the hanger in the usual manner and the trousers hung over the trouser bar of the hanger after which the hanger and garments may be hung in the closet by the hook.

By this construction the clothing is packed flat in a small compass and cannot slide and

shake around in the tray and become wrinkled.

I claim:—

1. A tray for luggage comprising a bottom, 5 a back and ends, a flap extending across said tray and stepped at its ends adjacent the back whereby slots are left between the flap and tray ends, a flexible section connecting said flap and back and a post centrally located on 10 the bottom of the tray adjacent the back thereof adapted to engage and retain a coat hanger.
2. A tray for luggage comprising a bottom, 15 a back and ends, a flap extending across said tray and stepped at its ends adjacent the back whereby slots are left between the flap and tray ends, a flexible section connecting said flap and back, and a post centrally located on the bottom of the tray adjacent the 20 back thereof adapted to engage and retain a coat hanger, said flap and flexible section being provided with a opening over said post.
3. A tray for luggage comprising a bottom, 25 a back and ends, a flap extending across said tray and stepped at its ends adjacent the back whereby slots are left between the flap and tray ends, a flexible section connecting said flap and tray back, a squared, stepped post centrally located on the bottom of the 30 tray adjacent the back, coat hangers, clips thereon provided with squared openings adapted to engage said post, said flap and flexible section being provided with an opening over said post.
- 35 In testimony whereof I have affixed my signature.

WALLACE H. BRACKEN.
